UNITED STATES PATENT OFFICE.

JOSEPH S. JAKUBOWSKI, OF WILMINGTON, DELAWARE.

VEHICLE WHEEL.

Application filed May 17, 1922. Serial No. 561,644.

To all whom it may concern:

Be it known that I, JOSEPH S. JAKUBOWSKI, a citizen of the United States, residing at Wilmington, in the county of New Castle and State of Delaware, have invented 5 certain new and useful Improvements in Vehicle Wheels, of which the following is a specification.

This invention has relation to improvements in vehicle wheels being directed particularly to the treads thereof and their adaptation to all kinds of road surfaces.

The principal object of the invention is to provide an anti-skid mechanism which 15 will be efficient and reliable and will come into contact with the road only where the same is soft and muddy or when it is covered with snow.

Another object of the invention is to provide 20 a simple and efficient structure of this nature which will be durable, comparatively inexpensive to manufacture, reliable in operation, and well adapted to the purpose for which it is designed.

With these general objects in view and others that will appear as the nature of the 25 invention is better understood, the same consists in the novel combination and arrangement of parts hereinafter fully described, 30 illustrated in the accompanying drawings and pointed out in the appended claims.

In the drawings forming a part of this application and in which like designating characters refer to corresponding parts 35 throughout the several views:

Figure 1 is a fragmentary elevation of the structure embodying my invention,

Figure 2 is a fragmentary plan thereof,

Figure 3 is a transverse section taken substantially on the line 3—3 of Figure 1,

Figure 4 is a longitudinal section taken substantially on the line 4—4 of Figure 2,

Figure 5 is a transverse section taken substantially on the line 5—5 of Figure 4 looking in the direction of the arrow, and

Figure 6 is a detailed perspective of a block used in conjunction with the structure of this invention.

Referring to the drawing in detail it will 50 be seen that 1 designates the main rim which may be of any preferred construction and attached to the felly of a wheel (not shown) in any suitable manner. This rim is provided at its edges with the turn-up annular flanges 2. A circular band 3 is adapted 55 to be situated in the rim 1 between its

flanges 2 as is shown to advantage in Figures 3 and 5. A plurality of blocks 4 are disposed about the band 3 in spaced relation to each other. Each block 4 comprises an elongated body provided on its inner face with a ridge 5 while the outer face thereof is flat throughout its major portion while the ends of this face are curved as at 6. These blocks 4 are held in place by the bolts 7 which pass through the apertures 8 in the blocks 4 and also through the band 3. The outer ends of the bolts are provided with sharpened projecting lugs 9. A cleat 10 is also situated along one of the sides of each of the blocks 4.

A pair of auxiliary rims 11 rest upon the curved portions 6 of the outer faces of the blocks 4 and these two auxiliary rims are provided with the extending outer flanges 12 which are engaged by the transversely extending bolts 13 so as to prevent cutting thereof and holding the rims in engagement with the blocks. A plurality of inwardly extending legs 14 are provided on the auxiliary rims 11 and they are arranged in pairs so as to engage the sides of the blocks 4 and the ends of each pair are engaged by the bolts 16.

The auxiliary rims 11 have therein suitable tires 17 which may be either of the solid variety or pneumatic variety or of any other suitable construction. It will thus be seen that the wheel provided with my structure when the same sinks to some extent into mud or snow the lugs 9 and cleats 10 will prevent skidding and slipping thereof. The present modification which I have described in detail refers only to the preferred example of my invention and it is to be understood that numerous changes in construction, and in the combination and arrangement of parts may be resorted to without departing from the spirit of the invention as hereinafter claimed.

Having thus described my invention what I claim as new is:

1. In combination, a band, a plurality of blocks fixed to the band in spaced relation to each other, and a pair of rims mounted on the blocks in spaced relation to each other.

2. In combination, a band, a plurality of blocks fixed to the band in spaced relation to each other, and a pair of rims mounted on the blocks in spaced relation to each other, a plurality of inwardly extending

legs mounted on the rims and arranged in pairs so as to embrace the blocks, and means for engaging the inner ends of each pair of legs for holding them tightly against the blocks.

3. In combination, a band, a plurality of blocks arranged about the band in spaced relation to each other, bolts passing through the band and the blocks, said bolts terminating in projecting lugs on the outer faces of the blocks, a pair of spaced rims mounted

on the blocks, legs depending from the rims and arranged in pairs so as to embrace the blocks and a bolt connecting the ends of each pair of legs.

In testimony whereof I affix my signature in presence of two witnesses.

JOSEPH S. JAKUBOWSKI.
